TOP

Barend Alexander Canter, Scheveningen,
NetherlandsApplication November 20, 1933, Serial No. 698,862
In the Netherlands December 2, 1932

4 Claims. (Cl. 46—40)

The invention relates to a top with a figure or figures pertaining thereto, the said figure or figures representing a person or persons, animals or objects of a different nature.

5 The purpose of the invention is the construction of a toy for children, which may also be used as an advertising means.

According to the invention the top is provided with a detachable piece representing a figure (as 10 for instance one or more persons, animals, etc.) which piece may be placed with a great deal of play and freely slideable in an axial direction by means of a support, into the spindle of the top, the said figure having two legs, feet or similar 15 extending parts, the length of which is taken so, that when the detachable piece is placed on the spinning top, the lower ends of the said legs or similar extending parts will be continuously in touch with the surface on which the top is spinning.

20 ning. The line connecting the said lower ends is lying outside of any plane of symmetry of the top, while the vertical line from the centre of gravity of the detachable piece passes between the said 25 lower ends and is at an appreciable distance from the vertical line through the centre of gravity of the supporting member.

The effect of placing the detachable piece on 30 the spinning top is that the tilting of the detachable piece about its lower ends, thereby touching the top, will impart a forward movement to the top, so that the figure will perform skating or dancing motions.

35 The friction of the lower ends of the figure on the surface on which the top is spinning will prevent the figure from spinning around with the top.

The invention is further explained by means of the drawing.

40 In the drawing Fig. 1 is front elevation partly in section and Fig. 2 is a partial side view.

In the embodiment represented in the drawing the top 1 is provided with a hollow spindle 2 having a funnel shaped upper end into which the supporting pin 3 of the Figure 4 may be introduced.

45 The supporting pin has a thinner portion ending in a rounded part 5. Of course this construction may be reversed, so that the top is provided

with a supporting pin and the figure with a hollow spindle fitting loosely on the supporting pin.

The legs 6 of the figure are bent backwards and are so long that when the supporting pin 3 is placed into the sleeve 2 of the top, they will touch with their lower ends 7, the surface on which the top is spinning, before the round part 5 touches the bottom of the hollow spindle 2.

5 As mentioned above the said lower ends 7 are bent backwards so that they are not in the plane 10 of the drawing, but are to be imagined a few centimetres back of the drawing, so that the line connecting the said lower ends crosses the axis of the top at right angles.

The figure may be made of a more or less resilient material, as for instance thin paste board.

15 When the top is spinning and the figure is placed with the pin 3 into the bore of the spindle 2, the figure will go through the motions of a skating or dancing person.

20

I claim:

1. A top having a bore at the centre thereof, extending downwardly a substantial distance, a stem adapted to extend into said bore, a figure attached to said stem and balanced with respect to said stem in one plane and unbalanced in a plane perpendicular to said first plane.

2. The device as claimed in claim 1 wherein the bore is of sufficiently greater diameter than the stem to afford play therein and the figure 30 has extensions downwardly of sufficient length to reach when assembled, the surface upon which the top is spun.

3. The device as claimed in claim 1 wherein the bore is of sufficiently greater diameter than 35 the stem to afford play therein and the figure has two diametrically opposed extensions downwardly of sufficient length to reach when assembled and in normal position, the surface upon which the top is spun.

40 4. A figure adapted to be used with a top and having a body portion, a median longitudinally extending stem and two diametrically opposite longitudinal extensions curved to the rear with respect to the frontal plane of the stem and body 45 portion and of greater length than said stem.

BARENDE ALEXANDER CANTER.
